W. W. McNAUGHTON.
VALVE LIFTING DEVICE.
APPLICATION FILED FEB. 16, 1920.

1,384,535.

Patented July 12, 1921.

UNITED STATES PATENT OFFICE.

WILLIAM WALLACE McNAUGHTON, OF BILLINGS, MONTANA.

VALVE-LIFTING DEVICE.

1,384,535.

Specification of Letters Patent. Patented July 12, 1921.

Application filed February 16, 1920. Serial No. 358,823.

To all whom it may concern:

Be it known that I, WILLIAM WALLACE McNAUGHTON, a citizen of the United States, residing at Billings, in the county of Yellowstone and State of Montana, have invented certain new and useful Improvements in Valve-Lifting Devices, of which the following is a specification, reference being had to the accompanying drawings.

10 This invention relates to devices to be used for compressing and retaining under compression the spring which normally surrounds the valve stem of an internal combustion engine while a retaining pin may be inserted or removed from the valve stem, thus allowing the valve member to be easily removed for grinding or repair and the valve seat to be exposed for grinding or repair.

20 The general object of the invention is to provide a device of this kind so constructed that the valve spring may be compressed with ease and quickly to thereby permit the removal of the valve and the exposure of the seat with the least amount of manual effort or power.

A further object is to provide a construction of this kind in which leverage is exerted to compress the spring, thus permitting very stiff springs of relatively large size to be readily compressed.

30 A further object is to provide a device of the character described which is adjustable as to length and is also adjustable in a direction at right angles to its length so that it may be used with engines of varied sizes or shapes without dismantling the engine or removing the manifold or other parts.

40 A further object is to provide a device of this character with means at its lower end for engagement with a valve stem, this means being in the form of an adjustable claw whereby it may be used upon valve stems of different sizes.

45 A further object is to provide a device of this character which is simple in construction and may be easily assembled or disassembled and will occupy but little space when it is assembled, thus adding to its portability.

50 Other objects will appear in the course of the following description.

My invention is illustrated in the accompanying drawings, wherein:—

55 Figure 1 is a side elevation of a spring compressor constructed in accordance with my invention;

Fig. 2 is an edge elevation of the construction shown in Fig. 1, partly broken away;

60 Fig. 3 is a perspective view of the upper section of the movable portion of the spring compressor;

Figs. 4 and 5 are perspective views of the second and third sections respectively;

65 Fig. 6 is a plan view of the claw;

Fig. 7 is a top plan view of the horizontal foot of part 20;

Fig. 8 is a side elevation of a modified form of terminal member.

70 Referring to these drawings, it will be seen that I provide a supporting frame section, designated generally 10, which is angular in form, that is provided with a limb or arm 11 extending vertically upward from the body 10, and a limb or arm 12 extending vertically downward from the body 10, at the opposite end of the body 10 from the limb 11. The limb 11 at its upper extremity is provided with a perforation 13 having 75 therein a pivoted latch 14. Midway of its length the limb 11 is provided with a strap iron loop 15 extending from one face of the rod from which the section 11 is made. At the lower end of the limb 11 there is provided a loop 16 which is open at one end. The body portion 10 is perforated, as at 17, and the limb 12 is provided along its length with a series of equi-distantly spaced perforations 18 and at its lower end with an 80 open collar 19.

85 Coacting with the limb 11 is a right angular rod 20, one edge of which is provided with the teeth 21. The angular arm 22 of this rod is thickened at a plurality of points, 90 as at 23, and these thickened portions are interiorly screw-threaded for engagement by a screw 24 having a wing head or other means whereby it may be rotated.

95 Coacting with the section 10 of the frame 100 is a second section 25 which has the form of an obtuse angle, and is made of a relatively flat rod. The vertical portion 26 of this section is perforated at a plurality of points, as at 27, these perforations being 105 adapted to register with the perforations 18 of the wing 12 of section 10, and the upper end of the section 25 is formed with an open collar 28 opening reversely to the collar 19 so that the vertical portion 26 of section 25 may have telescoping engagement with the vertical portion 12 of the section 10. Each of the loops or collars 19 and 28 is perforated for the passage of bolts 30.

Thus it will be seen that the vertical portion 26 of the section 25 has telescopic engagement with the limb 12 of section 10 and may be held in any adjusted position by the 5 bolts 30. The lower portion of section 25 extends downward and inward, that is to a position approximately beneath the vertical limb 11 and is provided with a plurality of perforations 31 and at its lower end 10 with a collar or upwardly extending loop 32.

Coacting with this section 25 is a third section 33 which is provided with perforations 34 adapted to register with the perforations 31 and which is formed in its upper 15 end with an open loop 35 adapted to embrace the section 25, the loop 32 of the section 25, of course, embracing this section 33 so that the section 33 has telescopic, adjustable engagement on the section 25. The 20 lower extremity of the section 33 is angularly bent and deflected into a plane at right angles to the plane of section 33 to form a pierced eye 36, and pivoted by a bolt 37 to this eye are the oppositely disposed jaws 38, 25 these jaws being tapered toward their extremities and disposed in the same plane. By loosening up on the bolt 37, these jaws may be adjusted nearer to or farther from each other and then the bolt tightened to 30 hold the jaws in their adjusted position.

Pivottally mounted upon the section 10 by means of a bolt or pivot pin passing through the perforation 17 is a lever 39, the shank of which is notched, as at 40, for 35 engagement with the latch loop 14, and the lower end of which is angularly bent and formed as a sector gear 41 having teeth which mesh with the rack teeth 21 on member 20. It will be obvious, therefore, that 40 when this lever is oscillated, the member 20 will be reciprocated.

While under most circumstances the three sections 10, 25 and 33 will fit a large number of different makes of engines, yet under 45 some circumstances it is necessary to use in place of the sections 25 and 33 the angular section 42 which is also made of a flat piece of metal, this section having a vertical limb formed with perforations 43 adapted to register with the perforations 18 and being formed at its upper end with the open loop 44 adapted to embrace the lug 12 of section 10. The laterally extending limb of this section 42 at its extremity is deflected into 50 a plane at right angles into the plane of the section 42 and pierced, as at 45, for the reception of the bolt 37 which engages the jaws 38 with the section 42. The section 42 is provided in order to give a new and different angle for the frame of the device and 55 permit the device to be used upon certain well known makes of gas engines where the frame as previously described is incapable of use.

60 In the practical use of my device, the

length of the frame composed of the members 10, 25 and 33 or of the sections 10 and 42 is adjusted to the size and make of the engine valve and of the engine. The jaws 38 are adjusted toward or from each other 70 to fit the size and shape of the valve stem. The arm 22 of member 20 is disposed across the head of the cylinder, and the screw 24 is adjusted against the head of the valve in the usual and ordinary manner. The jaws 75 38 are then inserted above the retaining pin in the valve stem and below the valve spring. Then the screw 24 is placed upon the valve head and adjusted thereon with the lever 39 in a horizontal position, that is the dotted line position in Fig. 1, and then by raising this lever A to the position shown in full lines in Fig. 1, the sections forming the frame will be raised relative to the part 20. The jaws will compress the valve spring and 80 enable the user to easily remove the retaining pin and thus permit the valve and valve spring to be readily removed and replaced. 85

It will be seen that this tool is adjustable 90 both as to length and laterally to fit engines of a large number of different sizes, and that the screw-threaded pin 24 may be adjusted in any one of the openings 23 so as to center the pin upon a valve head. The 95 leverage exerted is relatively great so that it has been found in practice that very heavy springs may be readily compressed to permit the removal of the spring and pin. The device may be readily disassembled by removing the bolts which hold the sections of the frame together and when so disassembled the parts take up very little room and can be easily packed for carriage for transportation. 100

It will be seen that I provide a construction of this character formed, generally considered, in two sections movable with relation to each other, one of said sections having means whereby it may be engaged 110 against a valve head, while the other section is shiftable by means of a lever to compress the spring, this second movable section being provided at its lower end with a claw or foot inserted above the retaining 115 pin and the valve stem and below the valve spring and preferably made with opposed jaws which are adjustable to fit the valve stem. It will be likewise seen that not only the lever operates to compress the spring, but that this is likewise attained by rotating the screw 24 so as to adjust the height of the supporting member 20 above the head of the valve. 120

I claim:—

1. An adjustable valve lifter and spring compressor comprising a member adapted to be disposed over the head of a cylinder and having a horizontal portion provided with a screw-threaded aperture, a screw 125 130

passing through the aperture, said member having a vertical portion, a second member vertically slideable upon the vertical portion of the first named member, said second 5 named member extending outward, then downward, and then inward, and being formed of a plurality of adjustable sections, the extremity of the second named member being provided with a claw for insertion 10 beneath a valve spring and around a valve stem, and a lever mounted upon one of said members and operatively engaging the other member to cause the rotation of the second named member upon the operation of the 15 lever in one direction.

2. An adjustable valve lifter and spring compressor comprising a member having a horizontal and a vertical portion, the horizontal portion being formed with a plurality 20 of screw-threaded apertures, a bearing screw adjustable through one of said apertures, a second member having a vertical portion sliding upon the vertical portion of the first named member and at 25 the lower end of this vertical portion extending outward, then downward, and then laterally to a position beneath the screw and being there provided with a claw insertible around a valve stem and beneath the spring, the second named member being composed of a plurality of 30 sections whereby it may be vertically adjusted as to length and laterally adjusted to cause the claw to register with the adjustment of the screw, and a lever mounted upon one of said members and operatively 35 engaging the other member whereby the second named member may be lifted relative to the first named member.

40 3. An adjustable valve lifter and spring compressor comprising a supporting member having a horizontal and a vertical portion, a screw passing through the horizontal portion, the vertical portion of the supporting member being toothed at its lower end, a second member slidably mounted upon the vertical portion of the first named member and extending outward from the first named member, then downward, and then inward, 45 and carrying a claw at its lower end, the claw being disposed beneath the screw, and a lever mounted upon the second named member and having a sector gear engaging with the teeth of the first named member 50 whereby the second named member may be lifted relative to the first named member.

4. An adjustable valve lifter and spring compressor comprising a supporting member adapted to be disposed over the upper 55 end of an engine cylinder and having a horizontal portion and a vertical portion, the horizontal portion being provided with a plurality of screw-threaded apertures, a screw adjustable in any one of said apertures, the vertical portion of the supporting member being toothed and having a horizontally disposed loop, a second member formed in sections, one of said sections having a vertical portion carrying a horizontally disposed loop, the vertical portion being adapted to be engaged with the loop of the vertical portion of the supporting member, and the loop of the said section of the second named member being open and adapted to be engaged with the vertical portion of the first named member, a second section vertically adjustable upon the first named section, and a third section adjustably mounted upon the second named section for adjustment laterally and carrying a claw at its lower end adapted to embrace a valve stem and be disposed beneath the spring thereof, and a lever pivoted upon the first named section of the second member and having a sector gear engaging with the teeth on the vertical portion of the supporting member.

5. An adjustable valve lifter and spring compressor comprising a supporting member adapted to be disposed over the upper end of an engine cylinder and having a horizontal portion and a vertical portion, the horizontal portion being provided with a plurality of screw-threaded apertures, a screw adjustable in any one of said apertures, the vertical portion of the supporting member being toothed and having a horizontally disposed loop, a second member formed in sections, one of said sections having a vertical portion carrying a horizontally disposed loop, the vertical portion being adapted to be engaged with the loop of the vertical portion of the supporting member, and the loop of the said section of the second named member being open and adapted to be engaged with the vertical portion of the first named member, a second section vertically adjustable upon the first named section and having its lower end extending downward and toward the axis of said screw, and a third section slidably mounted upon this downwardly and laterally extended portion of the second named section for adjustment longitudinally therealong, said third named section at its lower end having a horizontally disposed claw adapted to be disposed beneath and in alinement with the screw and to embrace a valve stem and to be disposed beneath the spring thereof, and a lever mounted upon the first named section of the second member and having a sector gear engageable with the teeth on the vertical portion of the first named member.

In testimony whereof I hereunto affix my signature.

WILLIAM WALLACE McNAUGHTON.
